UNITED STATES PATENT OFFICE.

WILLIAM PAYNE AND WILLIAM HENRY PAYNE, OF THAMESFORD,
ONTARIO, CANADA.

TRUSS.

SPECIFICATION forming part of Letters Patent No. 430,676, dated June 24, 1890.

Application filed July 16, 1888. Serial No. 280,125. (No model.)

To all whom it may concern:

Be it known that we, WILLIAM PAYNE and WILLIAM HENRY PAYNE, both subjects of the Queen of Great Britain, and both residents of 5
5 Thamesford, in the county of Oxford, in the Province of Ontario, Canada, have jointly invented certain new and useful Improvements in Trusses, of which the following specification, taken in connection with the accompanying drawings, forms a full, clear, and exact description.

The object of this invention is to provide an improved device or instrument to keep hernia reduced or to retain the intestines 15 within the abdominal cavity when the lining becomes torn or ruptured; and it consists of the improved construction and combination of parts of the same, as will be hereinafter more fully described and claimed.

Reference is had to the accompanying drawings already mentioned, wherein—

Figure 1 is a perspective view of a truss embodying our invention. Figs. 2, 3, and 4 are separate detail perspective views of the pad, 25 spring, and frame, respectively. Fig. 5 is a cross-sectional view of the frame and connections on the line $\alpha - \alpha$ of Fig. 4. Fig. 6 is a sectional view of the pad, showing a concave formed in its convex face. Figs. 7 and 30 8 are plan and cross-sectional views, respectively, of the buckle which secures the belt to the hooks on the slides secured in the frame. Fig. 9 is a perspective view of a double truss embodying our invention. Figs. 35 10 and 11 are perspective views of the extended frames used in a double truss. Fig. 12 is a cross-sectional view on the line $z - z$ of Fig. 9.

A designates a frame, which may be formed 40 flat; but it is preferably dished, as shown in Figs. 4 and 5, in order to form a recess for the spring F, and also to prevent the edges of said frame from wearing the clothes, and also to enable the buckles I and the ends of 45 the belt H, secured thereto, to work perfectly free on said frame.

B designates a pad, (shown in Figs. 2 and 6,) which may be secured to the frame A by any yielding pliable connection; but they are preferably secured together and held at any 50 required distance apart by a coil-spring C, a portion of which at one end is secured to the pad B, and a portion of which at the other end is secured to three sides of the frame A. This not only forms a secure connection, but 55 also forms an easy pliable support for the pad B, which permits it to give and adapt itself to the different strains thereon, as well as to the different positions of the body of the wearer. These pads B and frames A may be formed 60 of any suitable size or shape and of any suitable material; but they are preferably formed of metal and plated, because a very thin plate of metal is sufficient to form a strong and durable device. At the same time it is 65 light and not noticeable under the clothes of the wearer. This pad B and frame A may be and are preferably covered with chamois leather B³, or any other suitable material, to prevent the metal plate from coming in direct contact with the body; and the pad B 70 may be formed with perforations B' (shown particularly in Figs. 2 and 6) to permit of the circulation of air for the purpose of keeping the ruptured parts cool, and to prevent chafing, and this pad B may be formed with a plain convex face; but it is preferably formed with a concave B² (shown particularly in Fig. 6) in its convex face; and this concave is 75 made to conform with the shape of the rupture as much as possible, so that the edges of the convex face around the concave portion will rest on the sound part of the body around the rupture, while the slight concavity B² will come opposite and hold the intestines in 80 place. This concavity B² holds the intestines in the abdomen, at the same time the edges of the concave tend to draw the edges of the torn or ruptured lining together to permit them to reunite, so that when they have firmly 85 adhered together the truss may be dispensed with; but if the rupture were adjacent to the thigh, and if the end of the pad rested thereon when in proper position to keep the hernia 90

when in proper position to keep the hernia

reduced, the concave B² would leave too much space between the protruding bowels and the pad. In this case the concave portion B² might be dispensed with and the pad 5 with the plain convex face would be preferable, or the pad may slightly project at this point; but these latter conditions very rarely occur. They are described simply to show the adaptation of this pad to all forms of 10 rupture in any place or position, for this pad will work equally as well in this position as in front of the bowels, where ruptures most frequently occur, so that this truss may be adapted to hernia to keep it reduced when 15 in any place or position on the body.

D D and D' designate slides fitted to slots E E and E' in the frame A. (Shown particularly in Figs. 4 and 5.) These slides D D and D' are provided with flanges d², which extend 20 over on the frame A and hold said slides in place in their backward and forward movement in said slots E E E'. These slides D D D' are connected to one or more coil-springs F, which tend to draw the slides toward the 25 center of the frame A, and to each of these slides one or more hooks G are secured or formed integral therewith, as shown in Fig. 5, or separate slides may be used for each of the hooks G, and one or more slides may be 30 used, as required.

H designates the belt or band passing around the body, which belt holds the frame A and pad B, secured to said frame, to the body in proper position to keep the intestines 35 in the abdominal cavity. The ends of this belt or band H may be secured to the frame A by any suitable securing devices; but they are preferably secured thereto by a buckle I. (Shown particularly in Figs. 7 and 8.) The 40 slots I' in the buckles I engage with the hooks G, and the end of the belt or band H may be secured to the buckle I by any suitable securing devices; but it is preferably secured thereto by the pivotal eccentric-flap 45 I² of this buckle I. When this flap I² is in the position shown by dotted line i² in Fig. 8, the belt or band H may be readily and easily inserted between the flap I² and the body of the buckle and at any angle to adapt the 50 concave portion of the pad B to any part of the body, and when properly adjusted is rigidly held therein by adjusting the pivotal flap to the position shown by solid line I² in Fig. 8; and the coil-spring F may be in the form 55 of a flat or other suitable spring, or in the form of an elastic band or any other device that would form a tension on the ends of the belt or band H, which would hold the said belt and attachments safely and securely to 60 the body of the wearer, and both ends of the belt H, being permitted by this spring F to give a little, according to the different positions of the body of the wearer, the pressure of the belt and pad is equalized, so that it

will not catch and strain on one place more than another, but will be equalized over the entire length of the belt H and pad B.

J and J' are leg-straps, which pass down and around the leg to prevent the belt H and attachments from working upward or 70 moving out of place. The leg-strap J is attached to the frame A by the buckle I⁴ engaging with hooks G' on the slide D', and the latter is connected to the spring F and works in slot E', and flanges d² are formed 75 on this slide D' to hold it in the slot E', and a tension is formed on the leg-strap J by the spring F, all the same as before described, for securing the belt H to the frame A, and one end of the leg-strap J' is secured to the 80 leg-strap J. The other ends of these leg-straps J and J' are attached to the belt H by buckles K.

In forming the double truss shown in Fig. 9, each of the frames A of the single trusses 85 are extended at one side, and in one of the extensions of these frames is formed a series of perforations a', and the extension of the other frame with a perforation a⁵, and secured to which is a spring L, formed with 90 a stop a², the latter being fitted to the perforations a' and a⁵, and the extension of these frames A are provided with flanges a⁴, (shown in Figs. 10 and 11,) which overlap on the opposite frame, as shown in Fig. 9, for the purpose of preventing the frames A from being accidentally displaced laterally, and the perforations a' and a⁵ are on the same longitudinal line, so that when the frames A are moved lengthwise toward one another the perforations a' and a⁵ will come opposite, when the spring L will project the stop a² through these perforations a' and a⁵ and rigidly secure them together to completely prevent any accidental displacement lengthwise. 105

When wishing to adjust the pads B to or from each other to adapt them to a double rupture, the stop a², secured to the spring L, is raised out of the perforation a', and the extended portions of the frame A are 110 adjusted farther over on one another to shorten the space between the pads, or moved so that less of these extension-bars will overlap each other to widen the space between the pads, as required, and when once properly set they are securely held in that position by releasing the ends of the spring L, which immediately projects the stop a² 115 through the perforation a⁵ and one of the other perforations a', which rigidly and securely holds the pads from moving lengthwise to or from each other, but safely and securely holds them in the position to which they are adjusted.

In a double truss the leg-straps J J' cross 120 and are secured to each other at that point, and are also both secured one to each frame A by the buckles I⁴, and both to the belt H

by buckles K, and to three sides of each of the frames A a coil-spring C and pad B are secured similar to a single truss.

Having thus described our invention, we 5 claim—

The frame A, formed with one or more slots E and one or more slides D, fitted there-
to, and the slides D formed with one or more
hooks G and flanges d^2 , and spring F, in
10 combination with the belt H, spring C, and
pad B, as and for the purpose set forth.

In testimony whereof we affix our signa-
tures in the presence of the two undersigned
witnesses.

WILLIAM PAYNE.

WILLIAM HENRY PAYNE.
